UNITED STATES PATENT OFFICE

DAVID C. JONES, OF CHESNEE, SOUTH CAROLINA, ASSIGNOR TO DRAPER CORPORATION, OF HOPEDALE, MASSACHUSETTS, A CORPORATION OF MAINE

MECHANISM FOR WEAVING STRIPED CLOTH

Application filed October 16, 1929. Serial No. 399,919.

This invention relates to a mechanism for producing a striped effect or shadow stripes in cloth during the weaving operation.

5 The invention has for its object to produce this striped effect or shadow stripes by raising the whip roll at predetermined intervals for predetermined periods.

10 The invention has for its further object to provide a simple and efficient form of mechanism for securing the desired result which may also be readily embodied in existing looms.

15 These and other objects and features of the invention will appear more fully from the accompanying description and drawings and will be particularly pointed out in the claims.

As the invention relates to a feature which may be embodied in looms of various types, 20 and as but a few of the usual loom instrumentalities are necessary to an understanding of the invention, and as the whole subject matter outside of the present invention is well known and familiar to those skilled in the art, it is only necessary here to illustrate and describe sufficient portions of an ordinary type of loom in order to disclose a simple and preferred form of the invention.

25 In the drawings:

Fig. 1 is a side elevation partially broken away and with many of the parts removed of a loom of an ordinary type, together with a simple and preferred form of the invention embodied therein.

30 Fig. 2 is an end elevation of a portion of the construction shown in Fig. 1.

Fig. 3 is a detail showing a detent feature.

35 The loom illustrated is of an ordinary type comprising the side frames 1 and 2, the lay 3 supported by the pivotally mounted lay swords 4, the loom arch 5 connecting the side frames, the usual cam shaft 6, the cam 7 on the cam shaft for operating the cam follower 8 which in turn operates the connection 9 to the usual weft hammer, not shown, the warp beam 10 with its gudgeons 11 journalled in the side frames, and other well known features and elements, all operating 40 in the usual manner.

The sheet of warps 12 is shown as extending up and over a bar, shown as the usual whip roll 13, thence through the lease rods 14, then dividing into the shed 15, and thence 55 through the reed 16 and thence over the breast beam in the form of the completed cloth to the cloth roll, not shown.

It has been found that if the tension in the warp sheet between the warp beam and the shed be increased at intervals, there will be formed in the woven cloth transverse stripes, sometimes termed "shadow stripes," resulting from this variation in tension and this striped effect can be utilized to give a 60 pleasing design in the finished cloth by having the stripes occur at desired intervals and be of desired widths.

In this invention this striped effect is 65 formed by placing a bar, such as the whip roll 13, beneath the sheet of warps adjacent the warp beam or between the warp beam and the shed, and raising this bar or roll bodily at predetermined intervals for predetermined periods.

70 Preferably the usual whip roll 13 is utilized. This whip roll is freely journalled in bracket arms 17 secured to a shaft 18 journalled at the rear of the loom frame so that as the supporting bracket arms 17 rock with the shaft 18, the whip roll has a vertical bodily movement. In order to raise the whip roll 75 bodily at the required intervals and during the required periods to secure the desired striped effect, a simple and practical form of the supporting bracket arms 17 rock with the shaft 18, the whip roll has a vertical bodily movement. In order to raise the whip roll 80 bodily at the required intervals and during the required periods to secure the desired striped effect, a simple and practical form of the supporting bracket arms 17 rock with the shaft 18, the whip roll has a vertical bodily movement. In order to raise the whip roll 85 bodily at the required intervals and during the required periods to secure the desired striped effect, a simple and practical form of the supporting bracket arms 17 rock with the shaft 18, the whip roll has a vertical bodily movement. In order to raise the whip roll 90 bodily at the required intervals and during the required periods to secure the desired striped effect, a simple and practical form of the supporting bracket arms 17 rock with the shaft 18, the whip roll has a vertical bodily movement. In order to raise the whip roll 95 bodily at the required intervals and during the required periods to secure the desired striped effect, a simple and practical form of the supporting bracket arms 17 rock with the shaft 18, the whip roll has a vertical bodily movement. In order to raise the whip roll 100 bodily at the required intervals and during the required periods to secure the desired striped effect, a simple and practical form of the supporting bracket arms 17 rock with the shaft 18, the whip roll has a vertical bodily movement.

lower end at 27 to the connection 9 and at its upper end riding on the ratchet wheel 24. Over-running of the shaft 22 is prevented by a detent arm 28 pivoted at 29 on the loom arch, having a roll 30 at its free end engaging the serrated edge of the detent wheel 25 and yieldingly held in engagement therewith by the spring 31.

A pattern chain 32 is hung loosely on the sprocket wheel 20 and may be of any length desired and provided with any suitable number of risers 33 located at suitable points in the length of the chain. These risers are shown as presenting at their effective portions anti-friction rolls. An arm 34 is secured to the movable whip roll support such as the bracket arm 17 and extends down into the path of the pattern chain 32 and its risers 33, this arm 34 being curved at its lower end readily to cooperate with the rolls of the risers.

The operation of the construction will now be apparent. As the weaving operation proceeds and the cam shaft 6 is rotated, the sprocket wheel 20 will be rotated step by step, thus advancing the pattern chain 32 and carrying the risers 33 past the end of the arm 34 at predetermined intervals and during predetermined periods as determined by the character of the pattern chain and the timing of the mechanism. Each time a riser 33 passes the arm 34, the whip roll 13 is bodily raised, thus producing an increased tension in the warp shed adjacent the warp beam or between the warp beam and the shed resulting in a striped effect in the woven cloth.

There is thus presented a simple and efficient mechanism which may either be built into new looms or readily applied to existing looms for producing an increased tension in the warp sheet between the warp beam and the shed at predetermined intervals and for predetermined periods thereby to produce a transverse striped effect in the cloth.

Having thus described the invention, what is claimed as new, and desired to be secured by Letters Patent, is:

1. A loom comprising a whip roll, a support for the whip roll mounted on the loom frame and movable to effect vertical bodily movement of the whip roll, a sprocket wheel, a pattern chain on the sprocket wheel, risers on the pattern chain, an arm extending from the whip roll support into the path of the risers on the pattern chain, and means for rotating the sprocket wheel thereby to increase the tension in the warps at predetermined intervals for predetermined periods and produce a transverse striped effect in the cloth.

2. A loom comprising a cam shaft, a whip roll, a support for the whip roll mounted on the loom frame and movable to effect vertical bodily movement of the whip roll, a sprocket wheel, a pattern chain on the sprocket wheel,

risers on the pattern chain, an arm extending from the whip roll support into the path of the risers on the pattern chain, and means operated from the cam shaft for rotating the sprocket wheel, thereby to increase the tension in the warps at predetermined intervals for predetermined periods and produce a transverse striped effect in the cloth.

In testimony whereof, I have signed my name to this specification.

DAVID C. JONES.
